ICE SHAVING MACHINE

Alfred A. Jungbecker, Houston, Tex.

Application April 20, 1936, Serial No. 75,255

3 Claims. (Cl. 107—8)

This invention relates to ice shaving machines.

It is an object of this invention to provide an ice shaving machine which can be quickly and easily assembled and disassembled for cleaning 5 and repair.

It is the further object of this invention to provide an ice shaving machine which is particularly adapted to form ice shavings out of ice cubes of the type produced in electrical refrigerators.

10 It is the further object of this invention to provide an ice shaving machine embodying means for the formation of shaved ice masses.

It is a further object of this invention to provide an ice shaving machine as set forth in the 15 preceding object in which the shaved ice masses may be formed on a stock or bar for convenience in use.

It is a further object of this invention to provide an ice shaving machine as set forth in the 20 preceding two objects in which the shaved ice masses may be flavored to form confections.

Other objects and attendant advantages will appear in the following description of one practical embodiment of my invention illustrated in 25 the accompanying drawing, in which:

Fig. 1 is a view partly in section of an ice shaving machine, the portion in section being taken on a vertical plane extending through the horizontal axis of the machine.

30 Fig. 2 is a top plan view of the machine first illustrated in Fig. 1.

Fig. 3 is a detail view of a rotating member of the machine.

Fig. 4 is a section taken on line 4—4 of Fig. 3.

35 Fig. 5 is a fragmentary elevation of the machine.

Fig. 6 is a side view of an end cover for the machine.

Fig. 7 is an elevational view of a compressed 40 shaved ice mass of the type which may be formed within the machine, the view showing the mass as being formed on a stick.

The machine illustrated in the drawing comprises a housing 10 constructed with a supporting 45 leg 11. The leg 11 embodies a clamping mechanism consisting of a flange 12 and a screw 13 through which the machine is secured in place upon a table or other suitable support.

The housing 10 comprises a hollow vertical extension 14 through which ice is inserted to the 50 shaving apparatus later described. Such extension is designed to receive ice in the form of cubes as frozen in an ordinary electrical refrigerator, and to that end is constructed with a square passageway 15 slightly larger in cross-sectional area

than ice cubes of the type referred to. Such passageway is formed at an angle to the axis of the machine in order that blades of the cutting apparatus later described will engage with corners of the ice cubes rather than the sides, the object being to reduce the shock of engagement, and to obtain a shaving movement.

5 A cover 16 is provided for the upper end of the extension 14, and slidably mounted in such cover there is a plunger 17 for applying downward pressure to the ice within the extension 14. The plunger 17 comprises a rod 18 which extends through an aperture formed in the cover 16, a plate 19 mounted at the lower end of the rod 18 and designed for engagement with the ice, and 15 a head 20 secured to the upper end of the rod 18.

Rotatably mounted within the housing 10, there is a hollow member 21. Such member is supported at its forward end by a cylindrical extension 22 which extends through an aperture 23 20 in the forward wall of the housing, and at its rear end by a plurality of spaced lugs 24 which engage with a flange 25 on the rear end of the housing. It is formed with a central horizontal recess 26 which tapers outwardly towards the 25 rear of the housing, and is constructed with four exterior flat surfaces 27 which extend between the lugs 24, and with four slots 28 located below the passage 15 in the extension 14 and arranged at the forward edges of the surfaces 27.

30 Secured upon the flat surfaces 27 by means of screws 29, there are four plates 30 formed with cutting edges 31 which extend over the slots 28. These plates are formed with slots 32 for reception of the screws 29, instead of with apertures, in order to facilitate their removal and replacement.

The extension 22 on the member 21 protrudes beyond the forward end of the housing 10, the protruding portion 33 being reduced and threaded. 40 Screwed onto the threaded portion 33 in a manner to engage with a shoulder 34 at the rear end of such portion, there is a crank 35 equipped with a handle 36, which, due to the manner in which it is mounted upon the extension, serves 45 as a means for maintaining the member 21 in position.

The extension 22, in addition to being formed with a threaded portion for attachment for the crank 35, is formed with a bore 37 for reception 50 of a plunger 38. The plunger 38 comprises a rod 39 which extends through the bore 37, a plate 40 affixed to the inner end of the rod, and designed to engage with the ice shavings entering through the slots 28, and a removable head 41 55

screwed onto the outer end of the rod 38 through which force is applied to the plunger. A spring 42 mounted on the rod 39, intermediate the end of the extension 22 and the head 41, serves to normally maintain the plunger 38 in the position shown.

A plate 43 is provided for closing the rear end of the member 21. Such plate is formed with hooks 44, which, when the plate is secured in place, are inserted between the lugs 24 and turned to overlap such parts. Such plate is further formed with a lug 45 on its rear surface to facilitate turning, and with an aperture 46 which extends through the center of the lug 45. The purpose of the aperture 46 is to permit the insertion into member 21 of a stick or bar as hereafter explained.

The machine described is capable of being used either to produce loose shavings or to produce compact masses of shavings. To produce loose ice shavings, the cover 43 is removed and ice, preferably in the form of cubes of the type referred to, inserted within the extension 14. Ice in other shapes may, of course, be used, but the efficiency of the machine will be decreased due to a reduction in the size of the shavings. After the insertion of ice within the extension 14, the crank 35 is turned in a direction to produce clockwise rotation of the member 21 as viewed in Fig. 4, pressure at the same time being applied to the ice by means of the plunger 17. As the blades 30 are moved across the opening at the lower end of the extension 14 by the rotation of the member 21, they will operate to cut shavings from the ice. The shavings thus produced will drop into the interior of the member 21 and then slide downward on tapered inner surface of such member to the rear end of the housing where they can be caught in a suitable container.

To produce compressed ice masses, as previously mentioned, the cover 43 is secured in place upon the rear end of the member 21 and the machine operated in the manner just described. In such case, the shavings entering the member 21 collect against the cover 43, and when a sufficient amount of shavings has collected, the amount being determined from downward movement of the plunger 17, the plunger 38 is moved inward compressing the shavings against the cover to form a frusto-conical mass 47 as illustrated in Fig. 7. If desired, a stick or bar 48, to

serve as a handle, may be inserted through the aperture 46 and the shavings compressed upon such part. In addition, the ice masses may be flavored to form confections, or the liquid in the ice flavored before being frozen to attain the same result. Removal of the ice masses after formation is effected by detaching the cover 43 as will be readily understood.

The machine is disassembled by first unscrewing and removing the head 41 from the rod 39. The crank 35 is then unscrewed and removed from the extension 22, after which the member 21 and the plunger 38 can be withdrawn from the housing 10, and plunger 38 removed from the member 21.

What I claim as new is:

1. In an ice shaving machine, a casing, a rotatably mounted hollow member in said casing, said member being formed with an open end and with a slot in its side wall, cutting means on the exterior of said member overlapping the aforesaid slot, a hollow extension on said casing designed to receive ice and communicating with the interior of said casing adjacent said cutting means, a plunger in said extension for holding the ice in such part in engagement with said member, means for rotating said member to cut shavings from the ice, a removable cover for the aforesaid open end of said member formed with an aperture for insertion of a handle, and a plunger in the opposite end of said member arranged for movement in the direction of the aforesaid open end of said member to compress the shavings cut by said cutting means into a solid mass.

2. In an ice shaving machine, a housing, a hollow shaving cylinder rotatable therein, shaver blades thereon so that the shavings of ice will be deposited in said cylinder, a cap to be attached to said cylinder to confine the shavings, an opening through said cap to receive a handle member, and a plunger in said cylinder to compress the shavings about said handle.

3. An ice shaver including a housing, a rotatable drum therein, a shaver blade thereon, a rectangular opening in said housing for the insertion of ice cubes to be shaved, said opening being disposed so that the cube therein will be first contacted at a corner by said blade to obtain a shaving action.
